UNITED STATES PATENT OFFICE.

CHARLES E. BAILEY AND WILLIAM R. TALBOT, OF PROVIDENCE, R. I.

ORNAMENTAL-HEADED NAIL.

SPECIFICATION forming part of Letters Patent No. 248,269, dated October 18, 1881.

Application filed April 25, 1881. (No model.)

To all whom it may concern:

Be it known that we, CHARLES E. BAILEY and WILLIAM R. TALBOT, citizens of the United States, residing at Providence, in the county of

5 Providence and State of Rhode Island, have invented certain new and useful Improvements in Ornamental Heads for Nails; and we do hereby declare the following to be a full, clear, and exact description of the invention, such as 10 will enable others skilled in the art to which it appertains to make and use the same, reference being had to the accompanying drawings, and to the letters or figures of reference marked thereon, which form a part of this specification.

15 Our invention relates to improvements in ornamental heads or buttons for nails, tacks, screws, and other articles of a kindred nature; and it consists, essentially, of a head or button formed of sole-leather, pressed into shape 20 by suitable dies, and stained with transparent colors to resemble various kinds of natural wood, or colored to match upholstered furniture, said heads being connected to the nails or tacks, all as will be hereinafter more fully 25 described, and pointed out in the claim.

In the drawings, Figure 1 represents a perspective view of our improvement, and Fig. 2 a vertical section of the same.

Similar letters of reference indicate like parts 30 in both figures.

Referring to the drawings, A represents the head or button, which is formed of sole-leather, stained with transparent colors to suit, and

35 stamped into suitable shapes by heavy pressure between dies employed for such purpose, the head of the nail B being inserted in the under part of said head A during the process of manufacture.

In the operation of forming the complete device the soft texture of the leather head is compressed around the head of the nail by great pressure, the finished leather head presenting 40 a hard, compact, and solid body, capable of taking a high polish.

The advantages of our invention are such 45 that the nails thus formed can be readily driven into place without liability of the head being split, chipped, or broken, thereby remedying a serious defect which occurs in all other devices used for a similar purpose. We are also enabled to produce a neater and cheaper article, 50 combined with great strength and durability.

Having thus described our invention, what we claim as new and useful is—

As an improved article of manufacture, the 55 herein-described ornamental nail, consisting of the compressed-leather head A, stained in suitable colors, and provided with the nail B, substantially as specified.

In testimony whereof we affix our signatures 60 in presence of two witnesses.

CHARLES E. BAILEY.
WILLIAM R. TALBOT.
